UNITED STATES PATENT OFFICE.

HENRY B. DALLIMORE, OF BROOKLYN, NEW YORK.

GAS-HEATER.

1,373,307.

Specification of Letters Patent. Patented Mar. 29, 1921.

Application filed June 3, 1920. Serial No. 386,343.

To all whom it may concern:

Be it known that I, HENRY B. DALLIMORE, a citizen of the United States, and a resident of the city of Brooklyn, in the county 5 of Kings and State of New York, have invented a new and Improved Gas-Heater, of which the following is a full, clear, and exact description.

This invention relates to improvements in 10 gas heaters, and more particularly to a gas heater adapted to be positioned in the fire box of an ordinary coal range, an object of the invention being to provide a heater of the character stated which will function as a 15 heater for the water back, as well as for the oven and stove top to permit the use of the range for all ordinary purposes dispensing with the necessity for using coal.

A further object is to provide a device of 20 the character stated which can be quickly and easily assembled in a fire box, which dispenses with the use of bolts and nuts to connect the parts, and which can be readily taken apart, and damaged parts replaced 25 with but relatively small expense.

With these and other objects in view, the invention consists in certain novel features of construction and combinations and arrangements of parts as will be more fully 30 hereinafter described and pointed out in the claims.

In the accompanying drawings:—

Figure 1 is a view mainly in elevation but partly in section illustrating my improved 35 heater in the fire box of a coal range.

Fig. 2 is a view in section on the line 2—2 of Fig. 5.

Fig. 3 is a fragmentary perspective view 40 showing the manner of connecting the burner box to a standard.

Fig. 4 is a fragmentary sectional perspective view illustrating the distributing screen and adjacent parts.

Fig. 5 is a view in front elevation of the 45 burner partly in section.

Fig. 6 is a top plan view of Fig. 5.

Fig. 7 is a fragmentary sectional perspective view illustrating a damper attachment for the burner box.

50 1 represents an ordinary coal range, having a fire box 2, the latter provided with a water back 3 connected by water circulating pipes 4 and 5 with a water tank or domestic boiler 6.

55 In positioning my improved heater A in the fire box 2, I dispense with the ordinary

grate of the range, and support the standards 7 of the heater directly on the bottom of the ash pit 8.

The heater A is made with a pair of relatively wide open-work cast metal standards 7 supporting a top casting and a burner box 10 below the same.

The top casting 9 is made with depending slotted lugs 11 receiving wedges 12, the latter projected through the standards 7 and effectually securing the parts together.

The box 10 is made at its ends with slotted lugs 13 which are projected through suitable slots 14 in the standards 7 and secured by 70 means of wedges 15.

A coupling block 16 is secured to one standard 7 by means of a wedge 17 which is projected through a slotted lug 18 on the block, said lug being positioned through a 75 slot 19 in the standard.

The block 16 is made with a gas passage 20 which is supplied with gas by a nipple 21, the latter projected through an opening 22 in the front of the fire box. This opening is ordinarily provided to accommodate 80 the shaking shaft or trunnion of the grate.

The top casting 9 is formed at its ends with relatively large gas burners 23, having removable perforated burner plates 24, the latter preferably located under the stove holes 25, so that a cooking utensil can be 85 conveniently located over the same.

Gas pipes 26 and 27 connect the two burners respectively with the gas passage 20 and 90 have cocks 28 and 29 respectively therein to control the flow of the gas to the burners.

The burner box 10 has an inlet nipple 30 in its bottom connected by a pipe 31 with the gas passage 20 and having a cock 32 95 therein.

This burner box 10 is made with a forwardly extruded chamber 33 at its lower end having burner nozzles 34 in its top and other burner nozzles 35 are provided in the 100 upright wall of the box. The nozzles 34 and 35 direct the flame and the heat toward the water back 3 to rapidly heat the same and the draft over the top of the box is controlled by a hinged plate 36. This plate 105 may be given the desired angular disposition according to the shape of the water-back and its draft desired and I have illustrated in Figs. 1 and 2, two different positions of this plate.

A convenient manner of securing the plate at its angle of adjustment is to provide a

slotted curved arm 37 on the plate and clamp the same to one of the standards 7 by means of a bolt and wing nut 38.

The box 10 is preferably made with a removable back plate 39 secured by screws 40, so that the box and nozzles can be effectually cleaned out as occasion may require.

A semi-cylindrical screen 41 constituting a gas distributer, is located over the nipple 30 in chamber 33, and operates to distribute the gas throughout the box, preventing an over supply at any one set of nozzles, and a partition strip 42 is secured above the screen and coöperates with the screen in the performance of its functions.

I have illustrated in Fig. 7 a damper or draft controlling means which can be attached to the burner box and control the flow of air or inlet of draft between the box 10 and the water back 3. This draft control comprises a plate 43 which is secured to the outer face of the chamber 33 and which extends up to the bottom of the water back 3. A slide damper 44 is mounted on the plate 43 and this damper 44 and plate 43 have registering openings 45 to permit the air to pass through them and over the top of the chamber 33. A partition plate 46 is secured to plate 43, projects at right angles thereto and is positioned above the openings 45 so that this plate 46 acts as a deflector to compel the air to pass laterally as far as desired to give the necessary oxygen supply to the several nozzles of the burner box to aid combustion.

It will be noted particularly by reference to Fig. 7 that the burner nozzles 34 on top of the chamber 33 heat the bottom of the water back 3 and hence, these burners give efficient results to quickly heat the water.

It will thus be noted that I provide a heater which can be placed in the fire box of a coal range to heat the water back and supply all necessary heat for cooking purposes.

The device can be easily and quickly installed and the gas pipes and coupling block can be positioned at either end or either side of the device in accordance with the location of the fire box, whether it be at the right or left hand end of the range, as the parts are made easily changeable or reversible.

Various slight changes might be made in the general form and arrangement of the parts described without departing from the invention, and hence I do not limit myself to the precise details set forth, but consider

myself at liberty to make such changes and alterations as fairly fall within the spirit 60 and scope of the appended claims.

I claim:

1. The combination with a range having a water back in its fire box, of a gas heater in the fire box, burner nozzles on one side 65 of the heater, and a hinged plate carried by the heater and constructed to control the heat to direct the same against the water back.

2. The combination with a range having 70 a water back in its fire box, of a gas heater in the fire box, burner nozzles on one side of the heater, and a hinged plate carried by the heater and constructed to control the heat to direct the same against the water 75 back and a plate on top of the heater having burners below the stove holes of the fire box.

3. The combination with a range having a water back in its fire box, of a gas heater positioned in the fire box, burners at the 80 top of the heater, a burner box extending throughout the length of the heater for heating the water back, a pipe coupling block removably secured to one end of the heater, pipes connecting said block with said burners and box, cocks in said pipes, and an inlet nipple on said block projecting through the range front.

4. The combination with a range having a water back in its fire box, of a gas heater 90 in the fire box, said gas heater comprising a box having a forwardly projecting chamber at its lower edge, burner nozzles in the top of said chamber directing the flame and heat upwardly toward the bottom of the water 95 back, a plate secured to the burner box and extending upwardly to the bottom of the water back and having draft openings therein, and a damper on said plate controlling the draft of air through said draft openings. 100

5. The combination with a range having a water back in its fire box, of a gas heater in the fire box, said gas heater comprising a box having a forwardly projecting chamber at its lower edge, burner nozzles in the top of said chamber directing the flame and heat upwardly toward the bottom of the water back, a plate secured to the burner box and extending upwardly to the bottom of the water back and having draft openings therein, a damper on said plate controlling the draft of air through said draft openings, and a deflector plate projecting at right angles to the first-mentioned plate and located above the air passages in said plate. 110 115

HENRY B. DALLIMORE.
